J. S. Brown.

UNITED STATES PATENT OFFICE.

HORACE L. DUNCKLEE, OF BOSTON, MASSACHUSETTS.

IMPROVEMENT IN ARMY COOKING-STOVES.

Specification forming part of Letters Patent No. 39,802, dated September 8, 1853.

To all whom it may concern:

Be it known that I, H. L. DUNCKLEE, of Boston, in the county of Suffolk and State of Massachusetts, have invented a new and Improved Portable Cooking-Rangé, for the use of armies in camp and field, and in other similar situations; and I do hereby declare that the following is a full and exact description thereof, reference being had to the accompanying drawings, making part of this specification—

Figure 1 being a front elevation of my improved army range; Fig. 2, a top view thereof; Fig. 3, a central vertical section thereof, together with its oven, in place.

Like letters designate corresponding parts in all of the figures.

There are several desiderata in a good army-range which it is necessary to supply to insure complete success, and these desiderata must be considered not only singly, but in all of their several and mutual relations, so as to harmonize together, in order to produce the best effect. The first general desideratum is complete portability, which includes lightness, compactness, and convenience of packing, handling, setting up, and taking apart for transportation; second, adaptability in its operation to its proposed uses, including capability of successful working in all places however rough and inconvenient, suitability for the various kinds of cooking, and in the use and application of its furniture; third, simplicity of construction and operation, sufficient strength and durability.

My invention is intended to fulfill all of these conditions in the most direct and efficient manner, and is to be considered in this view as a whole in all the relations and results of its several parts.

In order to give it the greatest capacity with the least weight and bulk, in view of its portability, I make the body A broad and low, the height being just sufficient only to allow the necessary space for fuel within; and its utensils composing its furniture are arranged so as to occupy little or none of the internal space. This form also imparts the largest portion of the heat to the useful top surface, and least to lateral useless radiation. The form is cylindrical, as being the best for strength, compactness, and convenience. The material is sheet-iron, being light, not liable to break, and sufficiently rigid and firm to re-

sist injurious indentation and bruising. It only requires to be stiffened at the lower edge by a single hoop, *a*, of iron riveted to it. On account of the situations where it is intended to be used, it requires no bottom, which would only add to its weight, and would diminish its compactness. But for special uses a bottom may be added if desired, being constructed and attached substantially in the manner of the top B, which consists of a plane disk of cast-iron, either in one piece or in two pieces riveted together, as shown in the drawings. This top is provided with a flange, *b*, close to its outer edge, projecting downward at right angles to its surface. The flange fits closely into the upper end of the cylindrical body A, and the top is thereby held in place without any fastening, and thus fitting into the sheet-iron body keeps the same stretched out in good form, so as thereby to impart to it all the firmness and strength ever required. This simple method of uniting the top and body affords the utmost facility for setting up the range and taking it apart again for transportation. It also allows the furniture to be readily packed inside of the body, and the top to be simply laid over or under all. The articles are also readily removed again therefrom. The top has a suitable number of boiler-holes with covers in the usual manner, and a thimble is riveted to the body A to receive the smoke-pipe C. The range being constructed thus with a view to convenience and compactness, for portability, the furniture is nested together as well as the smoke-pipe, by having the successive numbers or joints a little smaller than the preceding. They are all of such size and so arranged as to be placed inside of the range-body A, and the whole are packed in a box made just large enough to receive the range. A box forty inches long, thirty-eight inches wide, and eighteen inches deep will hold a range and all its furniture and apparatus complete, sufficient to do all the cooking for a company of one hundred men upon, the whole range and apparatus weighing only three hundred pounds. The range can be unpacked and set up ready for use in five minutes, and repacked in three minutes.

The range, as thus far described, is not prepared for baking. I combine an oven, D, Fig. 3, therewith in the most simple, convenient, and efficient manner, and so that it occupies

none of the interior space of the range. It is made of sheet metal, of rectangular form, and entirely tight and close, except its under side, which is entirely open. It is simply placed upon the top of the range, which thus furnishes the bottom for the oven and transmits the heat thereto from the fire below. The open bottom of the oven thereby furnishes its door, since it is lifted off of the range when the viands are to be put in and taken out. The oven is made of such dimensions as to be packed for transportation inside of the range-body together with the other apparatus.

I am aware that the separate elements which constitute my invention may be found among other inventions, and therefore I do not claim the parts singly; but I am not aware that the complete and perfect combination of all adapted parts which make up my invention, so as to fulfill all the purposes designed harmoniously and efficiently, has ever been produced in any invention in those respects.

which I shall indicate in my claim, and therefore truly my invention.

What I claim as my invention, and desire to secure by Letters Patent, in a portable range or stove, is—

The combination of a sheet-iron cylindrical (or equivalently shaped) body A, strengthened and stiffened by a band or hoop, a, riveted or otherwise secured to the bottom thereof, with a cast-iron top, B, provided with a flange, b, projecting downward and fitting into the top of said cylindrical body, so as to form the sole connection between the body and top, substantially as and for the purposes herein set forth.

The above specification of my improved army-range signed by me this 7th day of March, 1863.

HORACE L. DUNCKLEE.
